LICENSE PLATE HOLDER

Norman E. Woods, St. Louis, Mo.

Application September 14, 1936, Serial No. 100,714

5 Claims. (Cl. 40—125)

This invention relates to holders for license plates for motor vehicles and the like, and its general object is to provide a plate holder that acts in the capacity of a frame for the plate, as well as a backing therefor, so as to not only add to the appearance of the vehicles carrying the same, but reinforces and protects the plate against material damage thereto.

A further object is to provide a license plate holder that secures the plate against vibration, and can be applied and removed with respect thereto in an easy and expeditious manner.

Another object of the invention is to provide a license plate holder that is adjustable to fit plates of various sizes.

A further object of the invention is to provide a license plate holder, that is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view showing my holder applied to a license plate with the latter fixed to a bracket of the usual construction.

Figure 2 is a sectional view taken approximately on line 2—2 of Figure 1, looking in the direction of the arrows.

Figure 3 is a front view of the holder per se.

Figure 4 is a sectional view taken approximately on line 4—4 of Figure 1 looking in the direction of the arrows.

Figure 5 is a similar view taken through an adjustable form of my holder.

Referring to the drawing in detail, and particularly to Figures 1 to 4 inclusive, it will be noted that the holder in that form includes a back 1 of arcuate formation, that has its side edges and upper edge bent or shaped to provide a flange 2 extending longitudinally of the upper edge of the back, and down the sides thereof to form a channel to receive the plate which for distinction is indicated by the letter A.

The plate is provided with the usual openings to receive bolt and nut connections B for securing the same to the upper arm C of a T-bracket D.

The holder is preferably formed from sheet

metal and includes a certain amount of inherent resiliency, and in order to prevent the plate from vibrating, I provide a clamping member that includes a screw 3 mounted in a flanged opening 4 centrally of and adjacent to the lower edge of the back 1, as best shown in Figure 3, with the head of the screw countersunk in the flange of the opening, as clearly shown in Figure 4. The screw has a collar 5 formed or otherwise secured thereon and engaged with the inner edge of the flange of the opening, so that the screw is held on the plate but is mounted for rotation therein, as will be apparent, and threaded on the shank of the screw is a tap 6 having a square cornered outer surface for the application of a tool thereto, such as a wrench or pliers for rotating the same, so that the tap can be disposed in engagement with the back or rear face of the plate A or arm C of the bracket D, to set up a binding action against the same due to the resiliency of the back and the curvature thereof. The clamping or binding action of the clamping member also causes the flange 2 to bind against the upper and side edges of the plate, as will be apparent upon inspection of Figure 4, consequently it will be readily seen that the plate is held rigid, and thereby vibration thereof is eliminated or reduced to a minimum.

In Figure 5 I have illustrated an adjustable form of holder, which includes a pair of sections cooperating to provide a back, and upper and side flanges, and one portion of the back is indicated by the reference numeral 7, while the other portion by the reference numeral 8. The portion 7 is provided with a slot 9 longitudinally arranged therein and preferably midway between the top and bottom thereof, for the purpose of receiving the bolt of a bolt and nut connection 10 which is mounted in or carried by the portion 8. By that construction, it will be seen that the sections are adjustable with respect to each other, to accommodate license plates of various sizes or lengths. It will be obvious that the portions of the flanges that extend along the top of the respective sections are telescoped mounted with respect to each other, to allow for the adjustment of the sections, and still retain a channel for the upper edge of the plate.

The form as shown in Figure 5 likewise includes a clamping member similar to that shown in the other form, for disposal against the plate, to prevent vibration thereof, as clearly shown in Figure 5.

It is thought from the foregoing description

that the advantages and novel features of the invention will be readily apparent.

It is to be understood that changes may be made in the construction and in the combination 5 and arrangement of the several parts, provided that such changes fall within the scope of the appended claims.

What I claim is:

1. A license plate holder comprising a back 10 for the plate, channel means formed on the upper and side edges of the back to receive the corresponding edges of the plate therein, screw means rotatably mounted in the back, and means threaded on the screw means and engageable with the plate for cooperation with the screw means to set up a clamping engagement between the channel means and the plate for securing the plate in the holder.
2. A license plate holder comprising a back 20 for the plate, channel means formed on the upper and side edges of the back to receive the corresponding edges of the plate therein, a screw rotatably mounted in the back adjacent to the lower edge thereof, means threaded on the screw 25 to provide a binding contact with the supporting bracket of the plate to set up a clamping engagement between the channel means and the plate for securing the plate in the holder.
3. A license plate holder comprising an arcu-

ate back for the plate, a channel flange on the upper and side edges of the back to receive the plate therein, and means carried by the back centrally thereof and adjacent to its lower edge to set up a clamping engagement between the flange 5 and the plate for securing the plate in the holder.

4. A license plate holder comprising a pair of adjustably mounted sections including a back for the plate, channel means on each section to receive the upper and one side edge of the plate, 10 means for securing the sections together for fitting association with the plate, and means carried by one of said sections to set up a clamping engagement between the channel means and the plate for securing the plate in the holder. 15

5. A license plate holder comprising a pair of sections, each including a back portion for the plate, channel flanges formed on the upper and outer side edges of the back portions to receive the corresponding edges of the plate therein, 20 said sections having their inner portions slidably mounted on each other and the channel flanges of the upper edge telescopically associated, means for adjustably securing the sections together, and means carried by one back portion to set up a 25 clamping engagement between the channel flanges and the plate for securing the plate in the holder.

NORMAN E. WOODS.
